CAR DOOR AND LOCKING MEANS THEREFOR

Application filed January 25, 1932. Serial No. 33,470.

My invention relates to improvements in car doors and locking means therefor.

One object of the invention is to provide a simple and inexpensive dumping door having automatic door locking means whereby a door may be slammed to closed position and automatically locked at each end thereof.

Another object of my invention is to provide means whereby one end of a door structure will positively be engaged by door locking means in advance of the opposite end of the door.

It is also an object of the invention to provide a preliminary locking means to hold the door in a partly closed position and to so adapt the parts that the door may be wedged to a fully closed position by movement of the door locking means.

Other objects and advantages of the invention will more clearly and fully appear from the description and claims hereinafter following.

In the drawings forming a part of this specification, Fig. 1 is a vertical sectional view of a portion of the so-called W-type hopper car, taken transversely of the car, and showing in front elevation my improved construction in connection therewith. Fig. 2 is a fragmentary side elevational view of that portion of the car shown in Fig. 1, illustrating my invention in connection therewith. Fig. 3 is a fragmentary view of the lower portion of the door as viewed on a line corresponding substantially to the line 3-3 of Fig. 2. Fig. 4 is a transverse sectional view taken through the door on a line corresponding substantially to the line 4-4 of Fig. 1. Fig. 5 is a fragmentary view of a portion of the car, showing the inner end wall of the hopper, with the door in closed position and the locking means in engaged position, said view being taken on the line 5-5 of Fig. 1. Fig. 6 is a view similar to Fig. 5 except that the door is shown in a partially opened position, and Fig. 7 is a sectional view taken through the door and hopper side wall, substantially on the line 7-7 of Fig. 2.

In said drawings 10 denotes one of the vertical side walls of the car, 11 a longitudinally extending reinforcing angle for the side

wall of the car, 12 one of the channel members usually employed to make up a girder center-sill of well known form, and 13 of the center-sill cover plate.

As customary in this type of car having multiple hoppers, the car is divided by transversely extending ridges, one of which is indicated by shedding plates 14 and 15. The hoppers are usually arranged in pairs transversely of the car, and since the construction of all the hopper sections is similar, only one of the same will be hereinafter described in detail.

Each hopper is defined by a sloping bottom hopper sheet 16, a vertical inside hopper sheet 17 disposed adjacent the center-sill, and an outer side hopper sheet 18, which slopes inwardly toward the longitudinal center line of the car. The lower margins of the sloping bottom hopper sheet 16 are reinforced by an angle iron member 19 which extends along the free edge of the sheet 16. The flange of the angle iron member 19 is bent and connection effected with flanges 20 of angle iron members 21 as indicated at 210, said members 21-21 act as reinforcing members for the side hopper sheets, due to the rigidity imparted by the outstanding flange 22.

Each of the discharge openings provided by the hopper arrangement is adapted to be closed by a sheet metal door indicated at 23, which is preferably flanged adjacent its hinged end as indicated at 24 and at its respective side edges as indicated at 25-25 and also adjacent its free edge as indicated at 26, said flanges 25-25 and 26 all extending from the inner side of the door and together providing a pan shaped member adapted to enclose the hopper structure as defined by sloping bottom hopper sheet 16, inner hopper sheet 17, and outer hopper sheet 18, the reinforcing angles 20-20 being spaced from the edges of their respective hopper sheets a sufficient distance to clear the said flanges 25. The door 23 is pivotally attached to the hopper structure by means of suitable hinges 27 pivoted on brackets 127 secured to the lower portion of plate 15 of the transverse ridge member.

A reinforcing beam 28 is secured to the door and disposed on the outer side thereof.

adjacent its free edge, and rigidifying corrugations 29 are pressed in the door plate to extend preferably in a direction at right angles to the beam 28 and extended to intersect the same, the crests of the corrugations 5 lying on the inner side of the door on the side opposite to the beam 28. The corrugations 29 are spaced from each other only a sufficient distance apart to permit the application of rivets or securing means as indicated at 30 for 10 the attachment of such parts as the hinges 27, and reinforcing beam 28.

Adjacent the lower portions of the discharge opening, I provide shouldered bracket members designated generally by reference 15 characters A and B, with which a pivoted oscillatable beam or bar C is adapted to operate to lock the door in a closed position in a manner which will be more fully pointed out hereinafter. The bar C is adapted to 20 be pivotally mounted intermediate its ends on a pivot 31 carried by a bracket 32 which is fixedly mounted on the door between corrugations. The bracket 32 is preferably formed with a base portion 33, and inner and 25 outer walls formed integrally therewith as indicated at 34 and 35 respectively. The inner wall 34 is spaced outwardly from the main body of the door plate sufficiently to permit the head 131 of pivot 31 to lie between the door plate and said inner wall 34. The bracket 32 is preferably so disposed on 30 the door as to provide for one end of the bar C to be of greater length than the other, said 35 longer side indicated at 36, being preferably the outer end or operating end of the bar which is adjacent the side wall of the car, and the shorter or inner end of the bar indicated at 37 being adjacent the inner hopper 40 wall of the car. The variation in the length of the arms insures the bar automatically gravitating toward a normal locked position and provides for automatic locking action of 45 the door as it is moved to closed position in a manner as will hereinafter be explained.

To lock the door in fully closed position, the respective arms of the oscillatable lever C which are extended beyond the adjacent sides of the door and cross the side wall of 50 the car, seat behind shoulders 38 and 39 respectively formed on the members A and B, the lever being displaced from its normal position during the door closing operation by the short arm 37 riding upon an angularly disposed surface 40 formed integrally with the bracket A. Intermediate the surface 40 and the main locking shoulder 38, there is formed, preferably integrally with the member A, an additional ledge 41 which is disposed slightly to the rear of shoulder 38 so that as the short arm 37, after displacement by contact with surface 40, commences to 55 resume its normal position it will engage behind said additional ledge 41 and maintain the door in a partially closed position.

The ledge 41 in addition to being disposed on a different level from the adjacent main ledge 38 is also preferably disposed out of alignment or in offset relation therewith, as indicated in Figs. 5 and 6. An inclined ledge 70 or runway 42, which extends between the respective ledges 38 and 41, is preferably formed integrally with the said member A and provided for the movement of the door from partially closed to fully closed position by further movement of the locking lever in the locking direction, the closing of the door being effected by wedging action as the arm 75 37 rides on the inclined runway 42. The incorporation of the two shoulder brackets in connection with the inner bracket A presents superior operating advantages as there is usually a tendency for the inner end of the door to slightly lag behind the outer end due to the fact that in closing the door the operator generally engages the door at the outer side only and on the side remote from the inner wall of the hopper; also the longer arm 80 36 of the lever C provides the operator with multiplied power to move the shorter arm 37 from the additional ledge 41 to the main supporting shoulder 38, thereby facilitating the wedging of the door to a fully closed position.

Adjacent each side edge of the door the lever C is guided in bracket members D and E respectively secured to the door and disposed adjacent the brackets A and B on the hopper structure, said bracket members D and E operating to limit swinging movement 95 of the lever in both directions, and also operating to space the said lever sufficiently from the main plane of the door to permit of necessary clearance for rivet heads and attaching flanges for the respective brackets and reinforcing beam 28. The members D and E are of angular formation, one flange 42 of each bracket lying against the door and the other flange 43 having a slot 44 formed therein through which the lever C extends. The 100 respective flanges are braced relatively to each other by integral flanges 45. The bracket E also has inner and outer walls formed integrally therewith as indicated at 46 and 47 respectively, and a locking cam F is pivotally mounted therebetween by means of a headed pivot 48 which passes through the respective walls, the inner wall 46 being spaced a sufficient distance from the door plate to accommodate the head of said pivot. 105 The cam F is adapted to swing about the pivot 48 to lock the lever C in closed position.

A fulcrumed member 49 is formed integrally with the bracket member B for the purpose of accommodating a removable tool 110 as indicated at 50, whereby the lever C may be readily displaced by bearing down on the outer end of said tool. The fulcrum member 49, which preferably consists of angularly related walls 51 and 52 outstanding from the 115 120 125 130

bracket B, is located intermediate the shoulder 39 and the rivets 53 securing the bracket B to the car structure. The fulcrum member 49 being thus located in close proximity to the bracket attachments, a rigid structure is provided and the tendency for the rivets to loosen and shear is materially reduced. Each of the brackets A and B is attached to the car structure and overlies the related reinforcing angle member 21, being formed to straddle the outstanding flange 22 of the said angle member 21 as best illustrated in Fig. 7, and the rivets 53 or other securing means by which the brackets are secured to the car structure, are disposed on opposite sides of the flange 20. The shouldered portion of each bracket A and B is spaced somewhat from its corresponding car side wall to permit the side flange 25 of door 23 to lie between said side wall and bracket when the door is in closed position, and the brackets are therefore built up with spacing means 54 through which the rivets 53 extend, said spacing means preferably being formed integral with the bracket and adapted to abut the outstanding flange 22 of the reinforcing angle member, thus providing a rugged construction.

When the door is in locked position as indicated in Figs. 1 and 2 the locking lever C rests behind the shoulders 38 and 39 of brackets A and B, and the load on the door is transmitted to said brackets through the medium of said bar, the door being maintained against deflection adjacent its edges by the Z-shaped beam member 28 and the respective marginal door flanges, while the body of the plate is maintained against buckling by the numerous corrugations 29 formed therein.

The manner of operation is as follows: Assuming the door to be in the opened position, the operator may stand at the side of the car and move the door towards closed position. As the door approaches closed position, the inner or shorter end 37 of the bar C engages the tapered face 40 of the bracket member A which serves to depress said inner end of the bar C, and raises the outer or longer end 36 above the bracket B.

As soon as the bar C clears the tapered face, the bar will engage with the secondary ledge 41 and retain said door in a partly closed position. The operator then bears down on the longer arm 36 which engages with a flared portion 55 leading to shoulder 39 of bracket B, of the lever, and the short arm riding on the inclined track 42 of member A wedges the door to a closed position. The parts are then locked in position by swinging the cam F into engagement with the bar as indicated in full line in Fig. 3. To release the door the cam F is disengaged from its corresponding locking bar and maintained in inoperative position by being

swung back to an overbalanced position as indicated in dotted lines in Fig. 3, the cam then resting on the upper surface 56 of the bracket E which is formed to support the cam in its overbalanced position. The operator then applies a suitable bar 50 on fulcrum 49 as indicated in Fig. 3 and bears down on the upper end of the same, thereby lifting the outer arm 36 of the bar C upwardly to the position indicated by dotted lines in Fig. 3, when the respective arms of the lever C will be released from their corresponding brackets and the door will open.

While I have herein shown and described what I now consider the preferred manner of carrying out the invention, the same is merely illustrative, and I contemplate all changes and modifications that come within the scope of the claims appended hereto.

What I claim is:

1. In a car, the combination with the car structure; of a dumping opening; a dump door adapted to close said opening; locking means including a beam member carried by the door and a shouldered member carried by the car structure and co-operable with said beam member to lock the door, said members being movable relatively to each other; a projecting part on the shouldered member adapted to serve as a fulcrum for an actuating tool for inducing relative movement between said beam and shouldered member, said projecting part being disposed intermediate the beam member and the car structure when the door is closed.

2. In a car having a hopper opening, the combination with a door adapted to close said opening; of a locking bar oscillatably mounted on the door; a shouldered member fixedly mounted on the car structure and co-operable with the bar to lock the door in closed position; and a projecting part on the shouldered member adapted to serve as a fulcrum for an actuating tool by which the bar may be unlocked, said fulcrum being disposed intermediate the locking bar when the door is in closed position and the car structure on which the shouldered member is mounted.

3. In a car having a hopper opening, the combination with a door adapted to close said opening; of a locking bar oscillatably mounted on the door; a shouldered member having a web portion fixedly mounted on the car structure and co-operable with the bar to lock the door in closed position; and a projecting part disposed on the shouldered member intermediate the shoulder and the fixedly mounted web portion, said projecting portion being of angular form and adapted to serve as a fulcrum for an actuating tool by which the bar on said door may be oscillated.

4. In a dump car, the combination with the side wall of the car; of a dumping door

having a marginal flange turned upwardly from the main plane of the door and overlapping the side wall of the car; a reinforcing member secured to the side wall of the car, said member having an outstanding flange contiguous with the door marginal flange; a beam member carried by the door and extending across the plane of the side wall; and door retaining means on the car side wall co-operable with the beam to retain the door in closed position, said door retaining means being formed to straddle the outstanding flange of the reinforcing member and secured on the opposite sides thereof.

5. In a dump car, the combination with a sloping bottom wall and side walls together defining a hopper opening; of a door adapted to close said opening; of a reinforcing marginal flange on the side edge of the door extending substantially in the plane of the hopper sheet; a reinforcing member for the side hopper plate disposed outwardly beyond the flange of the door; a shouldered member secured to the side sheet, said member being adapted to intersect the reinforcing member and being riveted to the side sheets on opposite sides of said reinforcing member; and a locking member on the door 20 co-operable with said shouldered member to lock the door in closed position.

6. In a dump car, the combination with a metallic door; of a locking bar pivotally mounted on the outer side of the door, said bar projecting beyond the side edges of the door; reinforcing marginal edges at the side edges of the door, said marginal edges being turned in a direction away from the locking bar; and brackets secured to the door plate 35 adapted to space the locking bar from the door plate, said brackets being also adapted to limit movement of the bar relatively to the door.

In witness that I claim the foregoing I
45 have hereunto subscribed my name this 21st
day of January, 1926.

ARGYLE CAMPBELL.
